Des. 203,213

Patented Dec. 14, 1965

203,213

SERVING SPOON

Warren Wilson, 4633 Roxbury Road,
Corona del Mar, Calif.

Filed Apr. 30, 1965, Ser. No. 85,048

Term of patent 14 years

(Cl. D44—29)

Fig-2

Fig-3

Fig-4

Fig-5

FIGURE 1 is a perspective view of a serving spoon embodying my new design;

FIGURE 2 is a top plan view thereof;

FIGURE 3 is a side elevation thereof;

FIGURE 4 is a bottom plan view thereof; and

FIGURE 5 is an end elevation as viewed from the right end in FIGURE 2.

I claim:

The ornamental design for a serving spoon, substantially as shown.
